UNITED STATES PATENT OFFICE.

JOSIAH H. SMITH, OF PHILADELPHIA, PENNSYLVANIA, ASSIGNOR TO WILLIAM H. TIGERMAN, OF PHILADELPHIA, PENNSYLVANIA.

SUSPENSION-RAILWAY.

1,142,124.

Specification of Letters Patent.

Patented June 8, 1915.

Application filed August 19, 1914. Serial No. 857,476.

To all whom it may concern:

Be it known that I, JOSIAH H. SMITH, a citizen of the United States, residing at Philadelphia, in the county of Philadelphia and State of Pennsylvania, have invented 5 certain new and useful Improvements in Suspension-Railways, of which the following is a specification.

My invention relates to improvements in 10 suspension railways, the object of the invention being to provide an improved construction of longitudinal girder having at opposite sides, laterally projecting cantalivers supporting rail holding beams.

15 A further object is to provide a construction of the character stated which is especially adapted for use with suspension trucks having wheels at both sides of the longitudinal girder and supporting the car 20 suspended from the truck.

25 A further object is to provide a structure of the character stated which will be exceedingly strong and durable to withstand the strains and stresses to which it is necessarily subjected.

30 With these and other objects in view, the invention consists in certain novel features of construction and combinations and arrangements of parts as will be more fully 35 hereinafter described and pointed out in the claims.

35 In the accompanying drawings: Figure 1 is a view in side elevation illustrating my improvements. Fig. 2 is a view in transverse section. Fig. 3 is an enlarged view in transverse section through the longitudinal girder, and Fig. 4 is a view in horizontal section on the line 4-4 of Fig. 3.

40 1 represents my improved longitudinal girder which is supported on transverse girders 2, the latter mounted on uprights 3. The longitudinal girder 1 comprises parallel upper angles 4 constituting the upper chord of the beam and lower angle bars 5 constituting the lower chord of the beam. These 45 angle bars 4 and 5 have gusset plates 6 secured between them, and the gusset plates of the upper and lower chords are connected by vertical and diagonal angle bar struts 50 7 and 8 respectively.

55 The longitudinal girder is connected to the transverse girders by shear plates 9 and suitable filler plates 10 are located between the several angle bars and plates to permit the surfaces of the bars to come flush to-

gether and allow them to be securely riveted as shown. The vertical angle bar struts 7 have triangular plates 11 secured between them. These plates 11 are located at opposite sides of the girder and are strengthened 60 at their inclined edge by angle bars 12 and at their lower horizontal edge by channel bars 13. At the outer end of the channel bars 13, angles 14 are secured and in turn are secured to I-beams 15 supporting rails 65 16. The plates 11, angle bars 12, channel bars 13, and angles 14 constitute cantalivers, and as seen clearly in Figs. 3 and 4, these cantalivers are located at directly opposite points on the sides of the longitudinal 70 girder 1, and at the inner ends of the channel bars 13 bear against the vertical angle bar struts and insure a strong and rigid construction to withstand the lateral strains 75 at this point.

17 represents a suspended car supported by trucks 18 having wheels 19 mounted to run on the rails 16, and it will be noted that the trucks are provided with two pairs of wheels at each side of the longitudinal 80 girder so that the car is supported by the rails 16 at both sides of the girder, and the cantalivers operate to properly space the rail supports from the girder, and provide a strong and rigid mounting to sustain lateral 85 or endwise thrust and to insure a rigid trackage for the car suspension.

Various slight changes might be made in the general form and arrangement of parts described without departing from my invention, and hence I do not limit myself to the precise details set forth, but consider myself at liberty to make such changes and alterations as fairly fall within the spirit and scope of the appended claims. 95

Having thus described my invention, what I claim as new and desire to secure by Letters Patent is:

1. In a suspension railway, the combination with a longitudinal girder, comprising 100 upper and lower chords consisting of angle bars secured together with gusset plates between them, and struts connecting the gusset plates, of cantalivers secured to certain of the struts and projecting laterally from both sides of the girder, and rail supporting beams secured to the outer ends of the cantalivers, substantially as described. 105

2. In a suspension railway, the combination with a longitudinal girder, comprising 110

upper and lower chords consisting of angle bars secured together with gusset plates between them, and struts connecting the gusset plates, of cantalivers secured to certain of the struts and projecting laterally from both sides of the girder, each cantaliver comprising a triangular plate secured to the vertical struts, channel bars secured to the lower edges of the plates at opposite sides thereof, angles secured to the outer ends of the channel bars, I-beams secured to the angles, and rails on the I-beams, substantially as described.

3. In a suspension railway, the combination with uprights, transverse girders connecting the uprights, and a longitudinal girder secured to and suspended from the transverse girders, of triangular plates secured to the longitudinal girder at opposite sides thereof, channel bars secured to the opposite sides of the plates and to the longitudinal girder, angle bars secured to the inclined edges of the plate, angles secured to the outer ends of the channel bars, I-beams secured to the angles, and rails on the I-beams, substantially as described.

10 15 20

at the outer ends of the channel bars, substantially as described.

4. In a suspension railway, the combination with uprights, transverse girders connecting the uprights, and a longitudinal girder secured to and suspended from the transverse girders, of triangular plates secured to the longitudinal girder at opposite sides thereof, channel bars secured to the opposite sides of the plates and to the longitudinal girder, angle bars secured to the inclined edges of the plate, angles secured to the outer ends of the channel bars, I-beams secured to the angles, and rails on the I-beams, substantially as described.

25 30 35 40

In testimony whereof I have signed my name to this specification in the presence of two subscribing witnesses.

JOSIAH H. SMITH.
